ABSTRACT

An evacuable chamber having two coaxial ports and a roughing port permits a user to insert a probe into a vacuum system without bringing the vacuum system to atmospheric pressure. When the probe is inserted into the first coaxial port it actuates a valve on the roughing port to connect the chamber with a vacuum roughing pump. A vacuum tight seal is also formed between the probe and the first coaxial port when the probe is inserted. Further insertion of the probe is prevented by a stop until the chamber is evacuated. The stop is released, and a valve between the chamber and the second coaxial port is opened upon evacuation of the chamber. The probe can then be inserted into the vacuum system connected to the second coaxial port. When the probe is removed, the valve on the second coaxial port is closed by a spring, and then the valve on the roughing port is closed by a spring. When the probe is removed from the first coaxial port, the chamber returns to atmospheric pressure, which aids in closing both valves tightly.

WILLIAM P. KRUGER

AUTOMATED VACUUM PORT

BACKGROUND AND SUMMARY OF THE INVENTION

There are three common methods for transferring materials and instruments into and out of a vacuum system. First, the vacuum system may be brought to atmospheric pressure, the transfer made, and the system re-evacuated. Second, the personnel using the vacuum system may wear pressurized "space suits" to enable them to work within the vacuum system. Third, system of seals, ports, valves, and auxiliary pumps may be used to permit transfers while the vacuum system remains evacuated. The first method is time consuming and is unsuitable for some operations during which the vacuum chamber must remain evacuated. The second method, while it overcomes some of the limitations of the first method, is extremely expensive. These limitations of the first two methods can be overcome by the third. However, the third method is usually susceptible to human error since the valves must be operated in the proper sequence to avoid contaminating the vacuum system.

The present invention is an improved version of the third method. The appropriate valves open and close automatically in response to insertion or removal of a probe containing the material or instrument to be transferred to the vacuum system. The automatic operation of the apparatus minimizes the opportunity for human error and consequent vacuum system malfunction while it shortens significantly the time required to transfer material or instruments into or out of the vacuum system.

The automated vacuum port apparatus comprises an evacuable chamber with three ports attached to it. The first and second ports are coaxial and at opposite ends of the chamber so that the probe can be inserted through the chamber into the vacuum system. The third port is connected to a roughing pump. When the probe is inserted through the first port, it actuates a mechanism which opens a door-like valve on the third port to evacuate the chamber. Further insertion of the probe is prevented by a stop until the pressure in the chamber reaches a predetermined level. When the predetermined pressure is reached, further insertion of the probe actuates a mechanism which opens another door-like valve on the second port and permits the probe to pass into the vacuum system.

When the probe is withdrawn from the vacuum system the sequence of events is reversed. After the probe is withdrawn from the second port the valve on that port closes. Similarly, as the probe is withdrawn to the first port the valve on the third port closes. When the probe is completely withdrawn, the chamber returns to atmospheric pressure; and this pressure helps close both valves tightly.

DESCRIPTION OF THE DRAWINGS

The drawing shows a cross-sectional plan view of the preferred embodiment.

DESCRIPTION OF THE PREFERRED EMBODIMENT

As shown in the drawing a chamber 10 is formed by a bottom plate 12 and a housing 14 with a seal 11

between them. Coaxial ports 16 and 18 are situated in opposite sides of housing 14 about axis 15. A port 20, situated in the top of housing 14, is connected to a vacuum roughing pump (not shown). Port 18 is attached to a vacuum system 22. A probe 24 is shown inserted into port 16; an O-ring 26 in a groove 28 forms a vacuum tight seal between port 16 and probe 24. Probe 24 may be used for transferring many different materials or instruments into vacuum system 22, such as solid, liquid, or gaseous samples; ampoules; photographic plates; radioactive materials; and ionization chambers.

As probe 24 is moved toward the left, it engages inclined surface 30 of lever 32, rotating the lever as shown by arrow 34. As the lever is rotated, an elastomer seal 36, attached to lever 32, is pulled away from port 20. The elastomer seal and lever comprise a valve 37, and this opening of valve 37 allows the roughing pump to evacuate chamber 10. Further insertion of the probe is prevented by a lever 38, which acts as a stop and is attached to a swivel plate 42 through a bell crank 40. A plate 44 with a captive O-ring 46 is loosely attached to swivel plate 42 by spools 48. Swivel plate 42 in turn is attached to bottom plate 12 at pivot 52; and bell crank 40, to the swivel plate at pivot 54. The swivel plate thus acts with a high mechanical advantage on lever 38. Elements 42, 44, 46, and 48 comprise a valve 50 and the seating pressure on valve 50, provided by the pressure in chamber 10 and a spring 56, keeps lever 38 upright.

When the pressure in chamber 10 drops to approximately the pressure in port 18, the seating force on valve 50 is reduced to the force of spring 56. That force is low enough to allow probe 24 to rotate lever 38, as shown by arrow 58, while the probe is inserted further into chamber 10. As lever 38 rotates it opens valve 50, as shown by arrow 60, which allows probe 24 to pass through port 18 into vacuum system 22. A groove 62 in port 18 containing an O-ring 64 makes a seal with probe 24, greatly reducing diffusion of air from chamber 10 into vacuum system 22. Once the probe has been inserted into vacuum system 22, the probe can be left in there for an indefinite period of time.

Upon removal of probe 24 from vacuum system 22, valve 50 will be closed by spring 56 when the end of the probe moves past lever 38. The loose mounting of plate 44 on spools 48 allows O-ring 46 to seat squarely against the end of port 18 even with the low seating force applied by spring 56. When probe 24 clears lever 32, a spring 66 closes valve 37, disconnecting the roughing pump from chamber 10. Air will then fill chamber 10 as the probe is moved past O-ring 26, and the air pressure will aid springs 56 and 66 in closing valves 50 and 37 securely.

There are other means which could be used to restrain the insertion of probe 24, before it contacts lever 38, while chamber 10 is being evacuated. For example an electrical pressure sensing device inside the box could be connected to a solenoid-actuated stop, or a mechanical pressure sensing device, such as an evacuated bellows, could be connected to a mechanically actuated stop. Alternatively, the user could manually operate a mechanical stop. Also, servicing of all moving components inside chamber 10 is relatively simple since they are all attached to the removable bottom plate 12.

I claim:

1. A vacuum port apparatus comprising:
an evacuable chamber;
a first and a second port on the chamber for receiving a probe, the first and second ports each having seal means for making a vacuum tight seal with the probe; 5
a roughing port on the chamber connected to a vacuum pump;
first valve means for opening a passage between the chamber and the roughing port for evacuating the chamber in response to insertion of the probe through the first port; 10
stop means for inhibiting further insertion of the probe into the chamber until the pressure in the chamber reaches a predetermined value; and
second valve means for opening a passage between the chamber and second port in response to further insertion of the probe after the chamber reaches the predetermined pressure to permit the probe to pass through the second port.
2. A vacuum port apparatus as in claim 1 wherein: the second valve means closes the passage between the chamber and the second port in response to withdrawal of the probe from the chamber; and the first valve means closes the passage between the chamber and the roughing port in response to withdrawal of the probe from the first port. 25
3. A vacuum port apparatus as in claim 2 wherein the first valve means comprises:

- a lever mounted on a pivot within the chamber; a seal attached to a first end of the lever; and a spring attached to a second end of the lever and to a fixed portion of the chamber to force the seal against the roughing port for closing the passage between the chamber and the roughing port; whereby the probe, when inserted through the first port, engages the second end of the lever to pivot the lever, forcing the seal away from the roughing port.
4. A vacuum port apparatus as in claim 2 wherein the second valve means comprises:
a swivel plate pivoted within the chamber; a seal attached to the swivel plate; a spring attached to the swivel plate and to another fixed portion of the chamber to force the seal against the second port for closing the passage between the chamber and the second port; a lever pivoted within the chamber; and
a bell crank attached to a first end of the lever and the swivel plate; whereby the probe, when it is inserted into the chamber, engages the lever to pull the swivel plate and the seal away from the second port, opening a passage between the chamber and the second port.
5. A vacuum port apparatus as in claim 4 wherein the stop means comprises the second valve means.
